(57) CLAIM

The ornamental design for a cutlery storage as shown and described.

DESCRIPTION

FIG. 1 is a front perspective view of a cutlery storage showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof, shown without the divider for ease of illustration;

FIG. 10 is a rear perspective view thereof, shown without the divider for ease of illustration;

FIG. 11 is a front perspective view thereof, shown without the storage housing for ease of illustration;

FIG. 12 is a rear perspective view thereof, shown without the storage housing for ease of illustration;

FIG. 13 is a bottom perspective view thereof, shown without the storage housing for ease of illustration;

FIG. 14 is a front perspective view thereof, shown in environmental use; and,

FIG. 15 is a front perspective view thereof, shown in another environmental use.

The broken lines in the figures illustrates the portions of the cutlery storage that form no part of the claimed design. The broken line showing of the additional divider and storage housing in FIGS. 14 and 15 is for the purpose of illustrating environmental subject matter that forms no part of the claimed design. The dot-dash broken lines immediately adjacent to the claimed areas in FIGS. 2 and 11-13 represent the boundaries of the design and form no part thereof.
